(57) **CLAIM**

The ornamental design of a grill brush, as shown and described.

DESCRIPTION

FIG. 1 is a front perspective view of a grill brush;

FIG. 2 is a back perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof; and,

FIG. 8 is a back elevational view thereof.

The broken line representations in the figures illustrate portions of the article of manufacture that form no part of the claimed invention.
